UNITED STATES PATENT OFFICE.

GEORGE S. SMITH, OF PITTSBURGH, PENNSYLVANIA, ASSIGNOR, BY MESNE ASSIGNMENTS, TO PITTSBURGH SCREW AND BOLT CORPORATION, A CORPORATION OF PENNSYLVANIA.

METAL-WORKING MACHINE FOR MAKING PUNCHED NUT BLANKS.

Application filed October 8, 1925. Serial No. 61,196.

This invention relates to metal working machines and more particularly to machines for making punched nut blanks from a bar or rod of stock.

5 The type of machine now generally used for manufacturing square nuts includes a die over which the end of the stock is fed and a cooperating plunger or punch which cuts off the end of the stock and forces it through the die to form a rough blank of square cross section. A transfer finger then engages the blank and moves it into position over a finishing die where it is engaged and held by a positioning means such as a pair of spring 10 pressed blank engaging jaws.

Heretofore it has been impossible to adapt this type of machine to the manufacture of hexagon nuts merely by changing the dies for the reason that the difference in shape of 20 the cut blank prevented the transfer finger from properly positioning the rough blank in the jaws over the finishing die.

An object of this invention is to provide a nut making machine of the type set forth 25 which can be adapted for either square or hexagonal nuts by merely changing the dies.

A further object is to provide a machine of the type set forth having a transfer mechanism constructed and arranged to properly 30 position a nut blank with relation to the holding jaws so that the blank will be accurately positioned over the finishing die regardless of whether it is square or hexagonal in shape.

35 These and other objects which will be obvious to those skilled in this particular art are accomplished by means of this invention, the preferred embodiment of which is illustrated in the accompanying drawings, in 40 which Figure 1 is a view in elevation of a nut making machine constructed in accordance with this invention and embodying the preferred form of transfer mechanism. Fig. 2 is a horizontal transverse sectional view on the line 2-2 of Fig. 1. Fig. 3 is a vertical section on the line 3-3 of Fig. 2. Fig. 4 is a similar view on the line 4-4 of Fig. 2 and Figs. 5 and 6 are diagrammatic views showing the relation between the transfer mechanism and a nut blank at the beginning and end of the transfer operation respectively.

The illustrated embodiment of this invention is shown as applied to a well-known form of nut making machine having the usual re-

ciprocating plunger head 5 operated from a 55 crank shaft 6 driven through spur gears 7 and 8 by a pulley 9 from any suitable source of power (not shown).

The feeding and operating mechanism of the machine can be of any standard construction and a detailed description thereof is not necessary for the purposes of this application.

The feed mechanism (not shown) intermittently feeds the stock 10 into the machine 65 beneath the reciprocating plunger head. The latter is provided with a punch 11 which cooperates with a punch die 12 secured in a die block 13 for punching out the stock which is fed past the punch beneath a stripper 70 plate 14. The punched out slug drops out of the machine through a channel 15.

A blank forming cutting punch 16 is also secured in the die head 5 and cooperates with a blank forming die 17 secured in the die 75 blank at the blank forming station to form a rough nut blank 18 which is cut from the end of the punched stock. At this forming station and beneath the blank forming die 17 is an annular chamfering die 19 adapted to 80

chamfer the lower face of the nut blank when it is forced therewith by the descent of the punch 16 through the forming die 17. An ejector 20 is mounted for reciprocation within a bore 21 in the machine frame in axial 85 alignment with the chamfering die and is adapted to be actuated by a helical spring 22 so as to raise the rough blank away from the

chamfering die in the usual manner. A finishing station is located at one side of the 90 latter die and consists of a finishing die 23 for finishing the surface of the rough blank 18 when the latter is forced therethrough by the punch 24 secured to the plunger head 5. Blank engaging jaws 25 are pivotally 95 mounted in brackets 26 secured to the machine frame at the finishing station and are spring pressed toward each other by a spring 27, the inward movement of the jaws being limited by pins 28. The blank engaging ends 100 29 of the jaws are adapted to receive and hold the rough blank 18 in the proper position over the finishing die 23 so that the descent of the punch 24 will force the blank through the die and provide it with a more or less 105 finished surface.

The transfer mechanism for moving the rough blank 18 from the blank forming sta-

tion to the finishing station includes a transfer finger 32 which is mounted in the end of a reciprocating supporting bar 33 extending outwardly through a channel 34 in the frame 5 of the machine. The latter is reciprocated in timed relation to the operation of the machine by a lever 35 pivoted to a supporting bracket 36 and extending upwardly therefrom. The upper end of the lever is provided 10 with a pin 37 which cooperates with a cam 37^a provided upon the end of the crank shaft 6 for oscillating the lever and reciprocating the transfer finger.

Upon each descent of the plunger head 5 the 15 punch 11 punches a fresh opening in the stock 10 and the cutting punch 16 cuts off a fresh blank from the end of the stock and forces it through the forming die 17 into the chamfering die 19 where the lower face is chamfered in the usual manner. Upon recession of the 20 plunger head and cutting punch 16 the ejector 20 lifts the blank 18 out of the chamfering die to the position shown in Figs. 3 and 4. At this moment the cam 37^a actuates the lever 35 25 so as to move the transfer finger 32 inwardly against the blank 18 and the latter is thereby moved into position over the finishing die 23 between the blank engaging sections 29 of the spring pressed jaws 25.

As best illustrated in Fig. 2, a hexagon blank is cut from the stock bar in such a way that opposite sides of the bar form opposite flat sides of the hexagon so that the apex between two adjacent angular faces falls in the 30 center line of the stock bar. Cutting a blank in this way produces a minimum amount of waste.

It will be obvious from an inspection of Fig. 2 that while a square blank can be moved 40 from the blank forming station directly into the positioning jaws 25 so as to have the opposite flat sides thereof engaged by the opposed jaws, such a movement is impossible with a hexagon blank for the reason that if the blank in Fig. 2 is moved squarely into the holding 45 jaws the latter will engage opposite corners of the blank instead of opposite flat surfaces. The result would be a turning of the blank in the jaws under the pressure of the spring 50 27 upon withdrawal of the transfer finger 32 and a resultant misalignment of the blank with relation to the finishing die 23.

In order to eliminate this disadvantage and to present a hexagon blank to the holding 55 jaws in such a way that the latter will engage opposite flat faces of the blank, the transfer finger 32 is slightly offset from the center of the nut blank and the blank engaging end thereof is cut so as to form a notch or concave recess 40, the sides of which generally correspond in angularity to two adjacent sides of the nut blank. As a consequence 60 the engagement of the transfer finger with the nut blank 18 causes a turning movement 65 of the latter as shown in Figs. 5 and 6, due

to the offsetting of the transfer finger from the axis of the blank and to the angular recess formed in the end thereof so that the blank is presented to the positioning jaws 25 in such a way that the latter engage the 70 opposite flat faces of the blank. The result is that the blank is held firmly in the position to which it is carried by the transfer finger. There is no subsequent turning or twisting 75 the blank in the jaws and the following 80 descent of the plunger head 5 and plunger 24 forces the blank through the finishing die 23 and out of the machine.

The lever 35 has a bifurcated end 41 which 85 straddles the transfer finger supporting bar 33 between collars 42 and 43. The bar and finger are moved inwardly by the lever operating against the collar 43 and the latter is secured to the finger supporting bar by a breakable pin 44 so that if any undue resistance is encountered on the inward movement of the transfer finger the pin 44 will break before any damage can be done to the machine or parts. A helical spring 45 is interposed between the collar and the frame of 90 the machine for maintaining the collar in constant engagement with the operating lever 35.

What I claim as new and desire to secure by Letters Patent is:

95

1. A nut forming machine having in combination a blank forming die, a finishing die, reciprocatory means for transferring a blank from said forming die to said finishing die, the blank engaging face of said means being constructed and arranged so as to rotate said blank by engagement therewith.

100

2. A nut forming machine having in combination a blank forming die, a finishing die and means including a reciprocating finger for transferring a blank from said forming die to said finishing die, the blank engaging end of said finger being formed so as to partially rotate said blank upon engagement thereby.

105

3. A machine for forming hexagon nuts having in combination a hexagon blank forming station, a finishing station, spring pressed jaws for engaging the blank at said finishing station and means for engaging the blank at said forming station and for moving it into engagement with said jaws, the blank engaging portion of said means being formed so as to cause said blank to turn by engagement therewith.

110

4. A machine for forming hexagon nuts having in combination a hexagon blank forming station, a finishing station, spring pressed jaws for engaging a blank at said finishing station, a reciprocable transfer finger for moving a blank from said forming station into engagement with said jaws, said finger having an angular recess in the blank engaging end thereof for causing said blank to turn about its axis during transfer move- 115

120

125

130

ment so that opposed flat faces of said blank are engaged by said jaws.

5. A nut forming machine having in combination a blank forming die, a finishing die and a notched transfer finger having means for moving a blank from said forming to said finishing die, said means being offset from the center of the blank so as to effect the rotation thereof.

10 6. A nut forming machine having in combination a blank forming die, a finishing die and a reciprocatory transfer finger for moving a blank from said forming to said fin-

ishing die and movable along a line offset with relation to the center of said blank so as to turn said blank upon engagement therewith.

7. A nut forming machine having in combination a plurality of dies and a transfer finger for moving a blank from one to another of said dies and adapted to first engage one side of a blank so as to cause partial turning thereof by engagement therewith.

In testimony whereof, I have hereunto subscribed my name this 5th day of October, 1925.

GEORGE S. SMITH.
